UNITED STATES PATENT OFFICE

CARL M. PETERSEN, OF TRENTON, NEW JERSEY, ASSIGNOR TO CIRCLE F. MFG. CO., OF TRENTON, NEW JERSEY, A CORPORATION OF NEW JERSEY

PUSH-SWITCH SOCKET

Application filed February 14, 1928. Serial No. 254,290.

This invention relates to lamp sockets or equivalent electrical receptacle for receiving the plug of a lamp or an attachment and more particularly to a novel push switch assembly 5 therefor.

A primary object of the invention is to provide a simple and practical construction including relatively few parts thereby not only effecting economies in manufacture and assembly, but also enabling the parts to be made in such a way that they last longer in service and fully meet the underwriters' requirements.

A further object of the invention is to provide a construction which may be assembled with a minimum number of fastenings, the construction and arrangement of the switch parts being such that the fastenings hold the porcelain and screw shell members together 20 while the switch parts are resiliently clamped between them.

A further object of the invention is to provide a novel switch contact spring which serves not only as the center plug contact of 25 the socket but also assists in holding the operating or actuating means for the spring in assembled position.

With the above and other objects in view which will more readily appear as the nature 30 of the invention is better understood, the same consists in the novel construction, combination and arrangement of parts hereinafter more fully described, illustrated and claimed.

A preferred and practical arrangement of 35 the invention is shown in the accompanying drawings, in which:

Figure 1 is a side elevation of a socket constructed in accordance with the invention, the 40 socket being viewed from the side having the line wire terminal which connects with the center plug contact spring.

Figure 2 is a vertical sectional view taken on the line 2-2 of Fig. 1.

Figures 3 and 4 are vertical sectional views 45 taken on the line 3-3 of Fig. 2, Figure 3 showing the switch open and Figure 4 showing it closed.

Figure 5 is a transverse cross-sectional view 50 taken on the line 5-5 of Fig. 2.

Figure 6 is a detail perspective view of the push bar.

Figure 7 is a detail perspective view of the combined contact spring and center plug contact.

Figure 8 is a detail sectional view of a modified form of spring and center plug contact construction.

Similar reference characters designate corresponding parts throughout the several figures of the drawings.

The present invention includes in its organization a porcelain body block designated generally as A, an insulating disk B and a screw shell contact C, the same being held in assembled relation by the screws or equivalent fastenings 1 and 2 as shown in Fig. 2 of the drawings.

The fastening 1 engages directly with the screw shell contact C and also with the line 70 wire binding terminal 3 thereby to provide a direct current path from said terminal to the screw shell. The fastening 2 also engages with the screw shell contact 2 and passes through the insulating disk B and an opening 75 in the insulating body A to receive a nut 4 positioned in a recess of the insulating body block whereby this fastening merely serves as additional means for connecting the parts without performing any electrical function. In that connection it is to be noted that the fastening 2 serves to clamp the binding terminal 5 between the insulating body block

A and the disk B, the lower end of said line 80 wire terminal 5 being slotted or cut away as 85 indicated at 6 to avoid contact with the screw 2, the said screw however being also protected by the downwardly projecting collar 7 formed from the body of the block A. The line wire terminal 5 has arranged between 90 the upper face of its lower inturned portion and the underside of the porcelain block A, a spring contact finger 8 as will be readily observed from Fig. 5, the said finger therefore being in electrical contact with the terminal. 95 This contact finger is of substantially angular formation and has the offset portion 9 thereof arranged across the transverse channel or opening D in the body block which houses the combined circuit closer and center plug 100

contact designated generally as 10 (Fig. 7). The said combined circuit closer and center plug contact is of novel formation as will be observed from Figs. 3, 4 and 7, the same including a body portion which is doubled substantially upon itself to provide a base portion 11 which rests on and overlies the disk B and a reversely bent arm portion 12 which projects through a slit in the base B thereby to lie beneath the disk to contact with the center plug of the lamp. To assist in preventing lateral shifting or slipping of the body portion 11 of the spring the same is provided with the offset lugs 11^a adapted to fit in the notches 11^b of the block A as will be observed from Fig. 5. The upper or yielding arm 13 of the spring is provided with a central slot 14 having at one end thereof a depressed seat or keeper notch S while the free end 15 thereof is bent at an angle and adapted to be pressed into engagement with the end 9 of the contact finger 8 (see Figs. 3 and 4).

For the purpose of operating the arm 13 of the spring 10 to close the circuit through the lamp held within the screw shell C, a slidable push bar or actuator 16 is utilized.

This push bar preferably consists of a metallic strip or bar portion having the finger engaging knobs 17 and 18 at the ends thereof while the intermediate portion is provided with a down-turned and laterally offset guiding and holding arm 19, the same being adapted to ride in a recess 20 in the transverse opening D of the body A as shown in Figs. 2 and 5 thereby to assist in limiting the movement or throw of the push bar and to also have a sliding engagement with the upper surface of the insulating disk B to prevent the actuation of the yielding portion 15 of the contact spring except when the push bar is moved or actuated through the operator pushing either one of the knobs 17 or 18 as will presently appear. The portion of the body of the push bar adjacent the arm 19 is provided with a lateral recess having a pivot axis or hanger 21 which carries a shiftable cam member 22 whose lower portion normally rides in the slot 14 of the contact spring.

The said cam member 22 is provided with a straight edge portion 23 having therein a notch 24 which provides a keeper shoulder 25 while the opposite edge thereof is cut inwardly along divergent lines as indicated at 26 to provide clearance for the push bar when the latch is in the position shown in Fig. 4.

With the arrangement described it will be apparent that the upper arm of the contact spring is normally elevated so that the contact portions 9 and 15 are out of engagement. However, when the push bar 16 is moved by pressing against the knob 18 thereby to shift the bar from the position shown in Fig. 3 to the position shown in Fig. 4, the latch member 22 will be carried along so that the edge

23 has a camming action on the end of the slot 14 adjacent the seat S. The effect of this camming action is to press the upper arm 13 of the circuit closing spring and bring the parts 9 and 15 into engagement. When the knob 18 is pushed to its limit, however, the keeper shoulder 25 will snap over the edge of the slot and into the keeper notch or seat S and thus releasably hold the latch in engagement with the spring to maintain the switch closed. In this way the switch will remain closed and held against accidental opening until the operator positively pushes or moves the knob 17 to cause the shoulder 25 to be removed from the seat S. When this occurs the yielding arm 13 of the spring snaps away from the part 9 of the contact finger 8 and breaks the circuit which was previously closed through the lamp.

From the foregoing it will be apparent that the present invention provides a novel and practical construction wherein the combined circuit closer and center plug contact is held in its assembled position by reason of its being between the push bar or actuator therefor and the insulating disk B. And, by mounting the latch 22 which is shiftable in the slot 14 in such a way that it will have a camming effect on the spring 13 until the parts 9 and 15 are brought into contact and temporarily latched, accidental disengagement is prevented and efficient and reliable switch mechanism is provided.

The path of the current through the present switch may be traced as follows:—

Assuming that the current enters the binding terminal 3, it will pass through the screw 1 to the metallic screw shell member C, and from thence to the screw plug of the lamp (not shown), and through the lamp filament to the center plug contact 12. Since the center plug contact 12 is a part of the circuit closing arm 13, the current will pass to the end 15 of said arm and to the contact finger 9 (see Fig. 4) which is in electrical contact with the binding terminal 5 as will be apparent from Figs. 3, 4 and 5. The binding terminal 5 is of course connected with one of the line wires. When the actuator 16 is shifted to open the switch, that is, separate the parts 9 and 15 as shown in Fig. 3, the circuit through the lamp is, of course, broken.

Fig. 8 shows a modification wherein the center plug contact 12^a is connected to the circuit closing spring 10 by a fastening 12^b which penetrates the insulating disk B.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. In a device of the class described, in combination with a body, a contact carried by said body, and a spring carried by said body normally spaced from said contact and movable into engagement therewith to complete an electrical circuit; a shiftable push bar, and an actuator carried by said push bar for engagement with said spring to force same into engagement with said contact when the push bar is moved in one direction, said actuator being pivoted to said push bar whereby it is adapted to engage with the spring upon movement of the push bar in an opposite direction to be rotated to permit quick release of said spring.
2. In a device of the class described, the combination with a body, a contact carried by said body, and a spring carried by said body normally spaced from said contact and movable into engagement therewith to complete an electrical circuit; of a shiftable push bar, and an actuator pivoted to said push bar for cooperating with said spring to force the latter into engagement with said contact upon shifting movement of the push bar in a predetermined direction.
3. In an electrical lamp socket, a push switch construction comprising a contact member, a combined circuit closing and center plug contact spring member including a yielding arm portion having a slot, a slidable member, a member pivoted to said slidable member and adapted to ride in said slot whereby movement of the bar in one direction will cause the said pivoted member to bear against one edge of the slot to force the circuit closing arm downward into engagement with the contact and movement in the other direction will release said arm.
4. In a push switch for lamp sockets, a combined circuit closing and center plug contact spring said spring having a yielding circuit closing arm provided with a slot and a depressed keeper seat at one end of the slot, a slidable push bar, and means carried by the push bar for engaging with one end of the slot to depress the spring arm and releasably hold the push bar and the spring at the end of the movement of the push bar.
5. In a push switch for lamp sockets, a combined circuit closing and center plug contact spring, said spring including an arm constituting a center plug contact and a yielding arm having a slot provided at one end with a seat, and means for depressing said yielding arm comprising a slidable member, and a cam pivotally carried by said slidable member and having a shoulder adapted to enter said seat thereby to releasably hold the cam and spring to hold the spring contact arm depressed.
6. A push switch lamp socket construction including an insulating block, an insulating disk, a screw shell member, binding terminals
- carried by the insulating block, a fastening electrically connecting one of the line wire terminals and the screw shell member, another fastening connecting the screw shell member and the porcelain block and clamping the other line wire terminal in place but insulated therefrom, a combined center plug contact member and contact spring, and means for establishing electrical contact between said contact member and the line wire terminal which is not electrically connected with the screw shell contact.
7. In an electrical lamp socket, an insulating disk, an insulating block at one side of the disk and a screw shell contact at the other, a contact member electrically connected with a wire terminal, a combined circuit closing spring and center plug contact comprising a body portion adapted to lie against one side of the insulating disk and having one end bent back downwardly through the disk to provide the center plug contact while the other end of the body is reversely bent to provide a spring arm adapted for engagement with said contact, said arm having a slot, a slidable actuator mounted in the insulating block, a cam member pivotally carried by the slidable actuator and travelling in said slot whereby one edge of the cam will engage with one end of the slot to press the entire arm downwardly when the actuator is moved in one direction.
8. In an electrical lamp socket, an insulating disk, an insulating block at one side of the disk and a screw shell contact at the other, a contact member electrically connected with a wire terminal, a combined circuit closing spring and center plug contact member comprising a body of substantially S-shaped formation, one end thereof projecting through the fibre disk to constitute a center plug contact and the opposite end constituting a yielding circuit closing arm while the body lies against the insulating disk, said yielding arm having a slot and a depressed keeper seat at one end of the slot, a push bar slidably mounted in the insulating block, a cam pivotally carried by the bar and located in said slot and having a straight edge portion and a keeper shoulder, said straight edge portion being adapted to engage one edge of said slot when the bar moves in one direction and the keeper shoulder being adapted to rest in said seat when the bar reaches the limit of its closing movement.
9. An electrical lamp socket including an insulating disk, an insulating block at one side of the disk, a screw shell contact at the other side of the disk, a line wire terminal electrically connected with the screw shell, a second line wire terminal insulated from the screw shell, a contact finger electrically connected with the second named line wire terminal, and a spring having the ends thereof bent in opposite directions, one of the ends

of the spring passing through the insulating disk to provide a center plug contact and the other end overlying the intermediate portion of the spring which rests on the insulating disk and having a slot, a push bar slidably mounted in the insulating block, a cam pivotally carried by the push bar and adapted to travel in said slot, and means for releasably holding the cam in engagement with the spring at the end of the movement of the bar which closes the circuit.

10. In a push switch construction for lamp sockets, a spring having the ends thereof bent in opposite directions to provide a center plug contact and a yielding contact engaging arm provided with a slot, a seat at one end of the slot, a push bar having a laterally offset and downwardly extending guide arm and provided with an intermediate pivot axis, a 15 cam mounted on said pivot axis and lying in the slot of said arm whereby the cam is held in assembled relation to said pivot axis, and said cam having an edge portion adapted to engage with an end of the slot to depress the 20 spring when the push bar is moved and also having a shoulder operating in conjunction with said edge to engage said seat to releasably hold the cam and the spring arm to maintain the arm in a downward position.

30. 11. In an electrical device of the class described, in combination with a body carrying electrical terminals, a push switch mechanism also carried by the body including a normally-open circuit closing spring and a push 35 bar carried by and movable with respect to said push bar, and an actuator operable to engage the spring to move it to closed position and to hold the same in such position upon movement of the bar in one direction and to 40 release the spring upon movement of the bar in an opposite direction.

12. In an electrical device of the class described, in combination with a body carrying electrical terminals, a push switch mechanism 45 also carried by the body and including a normally-open circuit closing spring and a push bar, an actuator pivoted to said bar operable to engage the spring to move it in closed position and to hold the same in such position upon movement of the bar in one direction and to release the spring upon movement of the bar in an opposite direction.

55. 13. In a device of the class described, the combination with a body, a contact carried by said body, and a spring carried by said body normally spaced from said contact and movable into engagement therewith to complete an electrical circuit; of a shiftable push bar, 60 and an actuator pivoted to said push bar for cooperating with said spring by rotation relative to said push bar to force the latter into engagement with said contact upon shifting movement of the push bar in a predetermined 65 direction and to quickly release said spring

upon shifting movement of the push bar in an opposite direction.

14. In an electrical device of the class described, in combination with a body carrying electrical terminals, a push switch mechanism mounted in the body and including a circuit closing slotted spring, a push bar, and a tripping actuator pivoted to the bar and extending into the slot of the spring and including a portion arranged to act upon the spring by compression to close the circuit and to hold the spring in such condition when the push bar is moved in one direction, and to pivot with respect to the bar to release the spring when the bar is moved in an opposite direction.

15. In an electrical structure of the class described in combination with an insulating body carrying plug terminals, binding terminals fitted to the body, one of said binding terminals having a member engaging over one end of the body, a push switch mechanism including a contact member having a part thereof arranged at one end of the body and in metallic contact with said member of one of the binding terminals, and a common fastening device for holding said binding terminal and switch contact member in operative position, said common fastening being insulated therefrom.

In testimony whereof I hereunto affix my signature.

CARL M. PETERSEN.
